DES. 2069

Letters Patent No. 2069-Dated May 16, 1865.

Design for a Coffin.

The schedule referred to in these Letters Patent and making part of the same

Y'all whom it may concern:

Be it known that I, William W. Roberts, of the City and County of Hartford and State of Connecticut, have invented and or produced a new and original Design for Burial Caskets; and I do hereby declare that the same is described and represented in the following specification and accompanying photographic views, reference being had to the letters marked thereon.

In the accompanying photographic views A, is the side, it is the end configurated with ornamental moulding C. Base flattened corners. E is the rounded or curved lid proper. F. F are plain raised, rounded or curved panel, surrounded with a plain ogee moulding G, the whole combined to produce a rich design for a burial casket.

What I claim therefore and desire to secure by Letters Patent is

The design for a burial casket substantially as herein illustrated and described.
